UNITED STATES PATENT OFFICE.

CHARLES A. FRISBIE, OF SAN FRANCISCO, CALIFORNIA.

EXTENSION-TABLE.

1,277,710.

Specification of Letters Patent. Patented Sept. 3, 1918.

Application filed May 31, 1917. Serial No. 171,932.

To all whom it may concern:

Be it known that I, CHARLES A. FRISBIE, a citizen of the United States, residing at the city and county of San Francisco and 5 State of California, have invented new and useful Improvements in Extension-Tables, of which the following is a specification.

This invention relates to an extension table.

10 One of the objects of the present invention is to provide a novel, simple form of folding leaf, particularly adapted for use in connection with extensible dining tables and the like which are provided with a solid pedestal. Another object of the invention 15 is to provide a pocket supported by the pedestal for the reception of the leaves, and, furthermore, to provide a novel hinge and link connection between the leaves and the 20 pocket which permits the leaves to be quickly extended or folded into the pocket with the expenditure of little time and effort. Further objects will hereinafter appear.

25 The invention consists of the parts and the construction and combination of parts as hereinafter more fully described and claimed, having reference to the accompanying drawings, in which—

30 Figure 1 is a plan view of the table, showing it pulled out to permit the leaves to be extended.

Fig. 2 is a cross section of the table, showing the folding leaves extended.

35 Fig. 3 is a similar section, showing the leaves folded into the pocket.

Fig. 4 is a perspective view of a hinge employed in connection with the folding leaves.

Referring to the drawings in detail, A 40 indicates a solid pedestal, which, in the present instance, supports a table top consisting of two sections 2 and 3 which are adapted to be extended with relation to each other, as shown in Fig. 1. The extensible top section 2 is supported by a pair of sliding arms or draws 4, carried by a pair of stationary guides 5, and the extensible top section 3 is carried by a pair of slidably mounted arms or draws 6 which are also 45 supported by the stationary guides 5; the arms 4 being slidably mounted on the exterior side while the arms 6 are slidably mounted on the interior side of the guides 5, as shown in Fig. 1. The guides 5 are in 55 turn carried by a base plate 7 which is se-

cured on top of the pedestal. The base plate forms a rigid support for the guides 5 and the sliding arms supported thereby and forms a support and a pocket for a plurality of foldably mounted leaves, generally 60 indicated at B, C and D.

Each leaf member consists of two sections 8 and 9 which are hingedly secured together, as at 10, and each leaf member is adapted to be swung out of the pocket shown at 11 65 to assume the position shown in Fig. 2 or folded into the pocket to assume the position shown in Fig. 3, the depth of the pocket being determined by the height of the sliding arms 4 and 6 and the stationary guides 5. 70

The folding of the leaves or the extension of same with relation to the pocket is accomplished in the following manner: Secured on the base plate 7 is a pair of side sections 12 and 13. Suitably secured to the 75 upper edge of the side section 12 are three pairs of bearing brackets 14 and pivotally mounted in each pair of bearing brackets is a bail-shaped link member 15 to which each leaf section 8 is pivotally secured, as at 16, 80 by bearing brackets 17. Secured on the inner end of each section 9 is a bearing bracket 18, and pivotally mounted in each of said bearing brackets is a link 19 which is slidably mounted on a track member 20, there being one track member for each set of folding leaves, as shown by dotted lines in Fig. 1. The bearing bracket 18 is more clearly illustrated in the perspective view shown in Fig. 4. It not only forms a pivotal support for the links 19 but each bearing bracket is also provided with an extended supporting shoulder 21 and a downwardly turned stop member 22, the function 85 of which will be hereinafter described.

90 Positioned adjacent to the side section 13, approximately centrally of each set of folding leaves, is an angularly disposed guide member 23, and formed in the upper edge of the side section 13 is a recess or shoulder 24 for the reception of a latch 25, there being one latch secured on each leaf section. 95

In operation, with the main table top sections 2 and 3 closed or pushed together, 100 as shown by the dotted lines 26, it can readily be seen that the folding leaves will be contained in the pocket 11 and entirely hidden from view. If it is desired to extend the table and employ any of the leaves, it 105 110

is only necessary to pull out or separate the table top sections 2 and 3, as shown in Fig. 1. One, two or three of the folding leaves may then be extended by grasping 5 the upper leaf section 8 at the free end indicated at 8^a and swinging it about the bail-shaped link 15 in the direction of arrow a. This movement of the leaf 8 causes the lower leaf 9 to move forward on the inclined 10 guide 23 out of the pocket and at the same time causes the link 19 to slide forward on the guide track 20. One position of the leaves while they are being extended is shown in dotted lines at 30. A continued 15 movement in the direction of arrow a will cause the two leaf sections to assume the horizontal position shown in Fig. 2 when they are completely extended. The ends are here supported by the stationary guides 20 5 and the sliding arms 4 and 6, while the inner ends, which are hingedly connected, as at 10, are supported by the link 19 which at this point will assume a vertical position; said vertical position being maintained, first, by the link engaging the end 25 of the guide track 20, and, secondly, by engagement of the stop shoulder 22 with the upper end of the link. The link is, therefore, positively held in a vertical position 30 and cannot accidentally collapse or swing out of the vertical supporting position shown.

The link 19 in reality only supports the inner end of the leaf section 9, but the extension shoulder 21, formed on the bearing bracket 18, is sufficiently long to support the inner end of the leaf section 8, thereby permitting the link 19 to support both ends of the leaf sections 8 and 9 when extended. 40 Any number of leaf sections may be extended in this manner, if desired, and all or a portion of same may remain folded in the pocket 11, if desired, the folding operation of the leaves being accomplished when the 45 leaves are extended by lifting upwardly on the free end 8^a, as shown in Fig. 2. This causes the leaf 9 to pull the latch 25 out of its recess and swing the link 19 into the dotted line position shown. A continued movement 50 of the leaf 8^a, in a direction opposite to arrow a, will pull the leaf 9 back into the horizontal position shown in Fig. 3 and will simultaneously cause the leaf 8 to be folded on top of same. The main table top 55 sections 2 and 3 may then be brought together to reduce the size of the table as desired.

A foldable, extensible leaf constructed as here shown is particularly adapted for use 60 in connection with extension tables employing a solid pedestal, as the pocket required for the reception of the leaves is comparatively shallow and the link and hinge members provided occupy such small space and, 65 when folded, lie parallel with the leaves.

Each leaf section can be made so short that it may assume the position shown in Fig. 3 between the stationary guides 5 and 6.

While the leaves are here shown as employed in connection with an extension table 70 of the dining table type, it is obvious that they may have other applications. I also wish it understood that various changes in form, proportions and minor details of construction may be resorted to within the scope 75 of the appended claims and that I do not wish to limit myself to the specific design and construction here shown.

Having thus described my invention, what I claim and desire to secure by Letters Pat- 80 ent is—

1. The combination with a solid pedestal, of a base plate carried by the pedestal, a pair of guide members secured one on each side of the base plate, a pair of extensible 85 table top sections slidably mounted on the guides adapted to cover or uncover the base plate, a leaf member consisting of two hingedly connected sections adapted to be supported by the base plate, a pair of side sections forming with the base-plate a pocket 90 for the leaf sections, a link pivotally connecting one leaf section to one of the side sections, a guide track, a second link member pivotally attached to the second leaf section 95 slidably connected with the guide track, and means for securing said second link in a vertical position when the connected leaf is in a horizontal position.

2. The combination with a solid pedestal, 100 of a base plate carried by the pedestal, a pair of guide members secured one on each side of the base plate, a pair of extensible table top sections slidably mounted on the guides adapted to cover or uncover the base plate, 105 a leaf member consisting of two hingedly connected sections adapted to be supported by the base plate, a pair of side sections forming with the base plate a pocket for the leaf sections, a link pivotally connecting 110 one leaf section to one of the side sections, a guide track, a second link member pivotally attached to the second leaf section slidably connected with the guide track, means for securing said second link in a vertical 115 position when the connected leaf is in a horizontal position, and a latch secured to the second leaf section adapted to lock the free end of the leaf against upward movement.

3. An extension table including main, horizontally slidable, separable main sections and intermediate leaves, each of said leaves being formed in two sections hinged together, a link pivoted at one end to one 125 of the leaf members and at the other to a fixed side member, a guide track fixed to the base, and a link having one end slidable upon the track and the other end forming a support for the meeting ends of the leaf 130

sections when said sections are in closed position.

4. An extension table including main, separable members and intermediate filling section, each of which is composed of two members hinged together, a link pivoted to one member and to a fixed support and forming a fulcrum and distance guide about which the leaf is foldable or extensible, a bracket fixed to the meeting end of the companion leaf member having a downwardly extended shoulder, a link engageable with the bracket, and a guide track on the table base upon which the link is slidable, said link being arrested and vertically placed to support the meeting ends of the leaf when its members are extended.
5. An extension table having main recip-
- rocable members, a base, guides for said members, intermediate two-part leaves 20 hinged at their junction, a bracket and stop shoulder fixed to one of the leaf ends, a guide track, a link slidable thereon and adapted to be raised to a vertical position to engage the bracket, an inclined guide member upon which the end of the outer leaf member may slide to raise the leaf to a level, and a catch engageable to secure the leaf sections in a level position.
- 25 In testimony whereof I have hereunto set 30 my hand in the presence of two subscribing witnesses.
